UNITED STATES PATENT OFFICE.

MYRON A. SMITH, OF NEW YORK, N. Y.

COMBINED FILTER AND HYDRAULIC PRESS.

No. 880,588.

Specification of Letters Patent.

Patented March 3, 1908.

Application filed August 10, 1903, Serial No. 168,881. Renewed June 22, 1907. Serial No. 380,243.

To all whom it may concern:

Be it known that I, MYRON A. SMITH, a citizen of the United States of America, and resident of the city, county, and State of 5 New York, have invented certain new and useful Improvements in Combined Filter and Hydraulic Presses, of which the following is a specification.

My invention relates especially to means 10 and mechanism employed for separating cocoa butter from the solid particles of cocoa, and for similar or kindred uses, and has for its object the provision of a combined filter and hydraulic press wherein the material 15 is not only subjected to filtration, but to hydraulic pressure without intermediate handling of the material treated, or of the receptacles holding the same.

To attain the desired end my invention 20 consists in a combined filter and hydraulic press in which is comprised a supporting frame; a series of pairs of rings mounted therein, each pair of rings carrying filter cloths; heads between each pair of pairs of 25 rings; movable separating pieces between each pair of pairs of rings; a conduit for material to be treated leading to the space between the filter cloths, and a hydraulic plunger. And my invention also involves certain 30 other novel and useful combinations or arrangements of parts, and peculiarities of construction and operation, all of which will be hereinafter first fully described, and then pointed out in the claims.

35 In the accompanying drawings forming a part hereof, Figure 1 is a plan view of a combined filter and hydraulic press embodying my invention. Fig. 2 is a vertical, axial, sectional view thereof at line *a—a* of Fig. 1. Fig. 3 is a cross-sectional view at line *x—x* of Fig. 2, looking from the right, the preceding 40 rings being removed. Fig. 4 is a vertical sectional view at line *c—c* of Fig. 3.

Like numerals of reference, wherever they 45 occur, indicate corresponding parts in all the figures.

1 are the horizontal side pieces of the main frame, connected at one end to a pumping head 2, having a central conduit 3 there- 50 through. 4 is a valve stem for closing said conduit.

5 is a hydraulic head to which the opposite end of the side pieces 1 are connected.

6 is a hydraulic plunger or piston within 55 the head 5.

12^a are guide wheels carried by the plunger 6.

7 is a water supply pipe leading to the chamber within the head 5.

8 is a chain connected to suitable mech- 60 anism for drawing the plunger 6 back into the head 5.

9 are supporting legs.

10 is a pan for the reception of cocoa butter, or the equivalent passing from the press, 65 and 11 are heating pipes beneath the pan 10.

12 are interlocking rings made substan- 70 tially in accordance with Letters Patent of the United States No. 707,029 issued to me Aug. 12, 1902 for filter and hydraulic press member.

13 are filter cloths held at their edges be- 75 tween each pair of rings 12. The cloths 13 are perforated at their centers and provided with flanged rings 14.

15 are distending springs.

16 is a plate having passages 17, and 18 therein as indicated in Figs. 3 and 4 of the drawing, and transverse perforations 19 communicating therewith. Secured to each side 80 of plate 16 is a head or plunger 20. At the perimeter of the head 20 is a ring 21, its outer face being at a right angle to its axis, and its inner face curved so as not to present an abrupt, cutting angle to the filter cloth 85 with which it comes in contact. The head 20 has a central perforation 22 corresponding to the ring 14 of a filter cloth, and at the side of the perforation 22 a finger 23 arranged to support a ring 14, insuring accurate register- 90 ing of the parts.

24 is a packing gasket fixed in the head 20, and arranged to bear against the flange upon the filter cloth ring 14.

The face of each head 20 is provided with 95 conducting channels or grooves 25 leading to the perforations 19 communicating with the passages 17 and 18, as particularly illustrated in Fig. 3 of the drawing. For convenience in manufacture I have shown heads 100 20 connected to a central plate 16, but it is obvious such plate and heads might be made integral without departing from the spirit of my invention.

At each side of the main frame, parallel 105 with the pieces 1, are journaled eccentric bars 26 each provided with a gear 27 ar- ranged to be operated by a worm 28 upon a shaft 29, each shaft 29 bearing a miter gear 30.

31 is a handle for rotating the worm gears. Upon each plate 16 are pivoted separating pieces 32 carrying at their outer ends friction rollers 33 contacting with the eccentric bars 26.

In operation; the parts of the device being in the position indicated in the drawings, the valve stem 4 is turned and cocoa liquor or the equivalent is pumped into the conduit 3, 10 passing into the spaces between the filter cloths; the butter passes through the cloths, and the channels in the heads, and escaping into the pan 10. Pump pressure is applied until such pressure is inadequate to remove 15 any more butter, when the valve stem 4 is turned, cutting off communication between the pump and press. By now turning the handle 31 the separating pieces 32 are withdrawn, and then by applying hydraulic 20 pressure to the plunger 6 the heads 20 are forced into the rings 12, expressing the butter still remaining in the mass between the filter cloths. It will thus be seen that I provide a device acting first as a filter press, 25 and then as a hydraulic press, doing away with much handling of the material treated, saving time and expense.

Having now fully described my invention, what I claim as new therein, and desire to 30 secure by Letters Patent, is:

1. In a combined filter and hydraulic press, the combination with filtering receptacles and a plunger, of movable separating pieces.
2. A combined filter and hydraulic press in which is comprised a supporting frame; a series of pairs of rings mounted therein; each pair of rings carrying filter cloths; heads between each pair of pairs of rings; 40 movable separating pieces between each pair of pairs of rings; a conduit for material to be treated leading to the spaces between the filter cloths, and a hydraulic plunger; the whole combined and arranged to operate substantially as shown and described.
3. In a device of the character herein specified, the combination with a filter cloth having a perforation through its center encircled by a ring, of a perforated movable head, having a finger projecting from the side of said perforation adapted and arranged to engage the filter cloth ring, substantially as shown and described.
4. In a device of the character herein specified, the combination with a movable

head having a central perforation, a packing gasket fitting around said perforation, and a central filter-cloth support, of a filter-cloth resting against said head, substantially as shown and described.

60

5. In a device of the character herein specified, the combination with the rings carrying filter cloths of heads or plungers, arranged to enter said rings, and movable separating pieces for interposing between each pair of pairs of rings.

6. In a device of the character herein specified, the combination with the rings carrying filter cloths, of heads arranged to enter said rings; movable separating pieces for interposing between each pair of pairs of rings, and means for moving said separating pieces.

7. In a device of the character herein specified, the combination with a plate from which a head extends into a ring carrying a filter cloth, of a separating piece pivoted to said plate, substantially as shown and described.

8. In a device of the character herein specified, the combination with heads entering rings carrying filter cloths, of filter cloths, rings carrying said cloths, separating pieces connected to said heads, and means for simultaneously withdrawing said separating pieces.

9. In a device of the character herein specified, the combination with a ring carrying a filter cloth, of a head or plunger adapted to enter said ring, such head having a rim, the outer face whereof is parallel with the axis of the head, the inner face being curved, substantially as and for the use and purpose shown and described.

10. The combination with a plate from which a head extends, of a filtering ring, a filter cloth, and movable means for separating the head and filtering ring.

11. In a combined filter and hydraulic press, the combination with a filtering receptacle and plunger, of movable means for separating said filtering receptacle and plunger.

Signed by me at New York city, this 1st day of August, 1903.

MYRON A. SMITH.
